THREE-HIGH MILL

William Stringham, Franklin, Ohio, assignor to
The American Rolling Mill Company, Middle-
town, Ohio, a corporation of Ohio

Application August 6, 1935, Serial No. 34,937

5 Claims. (Cl. 80—39)

My invention relates to the structure of mills known as three high mills, more particularly where the middle roll is small in diameter in comparison with the outer rolls.

5 In such three high mills, particularly where used to roll packs of sheets it is customary to grind the middle roll with a "crown". That is to say, the middle roll is ground so that its center is thicker than its ends. The reason for this practice is to eliminate the excessive convexity of the active passes in the mill when in use, due to 10 spring of the rolls therein.

Customarily the outer rolls of the mill are ground truly cylindrical although sometimes they 15 are ground "hollow", i. e., slightly less in diameter at the middle than at the edges, and sometimes they are slightly "crowned".

20 The amount of "crown" or lengthwise convexity of the middle roll will vary with the type of work to be done.

Now in adjusting the screw on the rolls in a three high mill for accurate working, there has been considerable difficulty, due to the fact that if one screw applies more pressure to one end of 25 the middle roll than the other screw applies to its opposite end, the middle roll due to its lengthwise convexity becomes cocked or shifts its position. This changes the shape of the active pass of the mill when in use and seriously affects the 30 accuracy of operation of the mill on both the lower and the upper pass.

It is the object of my invention to do away with this difficulty, and I accomplish it by forming 25 collars or ridges on both ends of the upper and lower rolls of the mill sufficient substantially to equalize the amount of crown on the middle roll.

I am aware of the fact that in two high mills in order to prevent the surfaces of the rolls from 40 contacting with each other when the mill is running idle, and to prevent the rolls from becoming injured when they come together after a piece has passed through them, collars have been formed on the roll ends. My invention does not concern this idea, nor do I attempt to gain such an effect or to permanently space away the middle roll from all contact with the outer rolls. Indeed the central zone of the middle roll will ordinarily contact the outer rolls when the mill is 45 running idle, according to my invention.

50 I accomplish my object by that certain construction and arrangements of parts of which an example will be described in detail and has been illustrated in the drawing. The inventive features are set forth in the claims that are appended, to which reference is hereby made.

In the drawing, the figure is a view partially diagrammatic in nature of a three high mill. The diagrammatic feature is the amount of crown and height of roll end collar shown, which has been exaggerated for purposes of illustration. 5

I have shown as exemplary housings, the standards 1, 1, in which the bearings 2, 3 and 4 are mounted slidably, said bearings serving to rotatably mount the top roll 4a, the middle roll 3a and the bottom roll 2a, respectively. 10

The screws 5, serve to adjust the setting of the mill for operation.

It will be noted that the middle roll 3a is shown to be convex in longitudinal section. As an example it will be supposed that the diameter of 15 this roll at the central zone thereof is .015 inch greater than at the ends thereof.

The outer rolls 2a and 4a are illustrated as truly cylindrical in shape, and collars or ridges are formed at their ends each collar being approximately .0075 inch in height above the surface of the roll. 20

It can be seen that with such an arrangement the collars on the ends of the outer rolls will contact with the ends of the middle roll, when the 25 centers of the outer rolls contact with the central crowned zone of the middle roll.

This accuracy of relationship need not exist but need only be substantially approximated.

Of course the piece being operated upon will 30 not be wide enough to contact with the collared portion of the outer rolls.

As so arranged there will be no danger of cocking the middle roll upon adjustment of the screws, no difficulty due to the first screw to be turned 35 down throwing the mill out of transverse adjustment so that the second screw cannot be turned down an equal amount. The difficulty attendant upon rolling of quite wide, thin packs or pieces where accuracy of active pass shape is 40 of particular importance, has been largely avoided in practice by the use of the above described simple expedient.

It is desirable to form the collars on the outer rolls rather than the middle roll because in 45 grinding the convex middle roll to desired shape the machinery normally employed will be interfered with by the collars. It would, however, be a feasible mode of carrying out my invention to place the collars on the middle roll. 50

Having thus described my invention, I will set forth in the following claims the invention inherent therein upon which I ask for Letters Patent:—

1. In a three high mill having a middle roll 55

- which is convex in longitudinal section, upper and lower rolls having at the ends collars abutting against the middle roll and of a height such as substantially to compensate for the greater diameter of the middle roll at its central zone, when the mill is idle, for the purpose described.
2. In a three high mill having a middle roll which is convex in longitudinal section, upper and lower rolls abutting the same at the middle zone thereof, when the mill is idle, the contour of said upper and lower rolls differing from that of the middle roll so as not to be a counterpart thereof, the ends of the respective rolls beyond the working area thereof being such that when the three rolls are brought together at the middle zone thereof, they will abut each other at the ends also.
3. In a three high mill having a middle roll which is convex in longitudinal section and upper and lower non-conforming rolls, the upper and lower rolls so formed at the end beyond the working faces thereof, that when their surfaces substantially abut the middle zone of the middle roll, they will abut the middle roll at the ends thereof also.

4. In a three high mill having a middle roll which is convex in longitudinal section and upper and lower non-conforming rolls, the said rolls so formed at the ends beyond the working faces thereof, that when their working faces abut at the middle zone, when the mill is idle, they will abut each other at the ends beyond the working faces, at the same time.

5. A three high mill having outer rolls and a middle roll of smaller diameter, said middle roll being convex in longitudinal cross section, and means for preventing misalignment of the rolls upon actuation of the screw down, said means comprising annular raised portions at the ends of the outer rolls of sufficient height to offset the difference in diameter between the central part of the middle roll and its ends, said raised portions acting to prevent an approach of the ends of the outer rolls to the ends of the middle roll closer than would be permitted by the diameter of the central part of the middle roll without cocking of said roll.

WILLIAM STRINGHAM. 25
